UNITED STATES PATENT OFFICE

WALTER O. BROWN, OF DETROIT, MICHIGAN

DISPLAY RACK

Application filed September 8, 1931. Serial No. 561,689.

This invention relates to display racks for merchandise of various kinds but is more particularly adapted for the display of bananas and is herein shown and described but it is 5 to be understood that articles of various kinds may be displayed therein without departing from the scope of the invention.

An object of the invention is in the provision of a display rack comprising one or 10 more strips of fabric so held as to provide a loop or loops which will closely conform to the shape of a hand of bananas.

Another object of the invention is in the provision of a display rack which is so constructed as to permit a plurality of hands of bananas to be displayed therein and which will permit any one of the hands to be removed from the rack without disturbing or 20 changing the position of any of the other hands.

Another object of the invention is in the provision of a fabric support for hands of bananas which will help maintain the bananas in good condition and which will prevent the lower bananas in the hand from becoming damaged due to the weight of the uppermost bananas of the hand pressing thereon.

A still further object of the invention is 30 in the provision of a display rack of this character which will prevent the bananas of one hand coming in contact with the bananas in another hand in the row thereabove.

Another object of the invention is in the provision of a display rack in which the fabric support for the bananas is arranged in 35 stepped relation so that the uppermost layer of each hand of bananas in the various rows is exposed to view.

Another object of the invention is in the provision of a display rack comprising a substantially box like structure the upper face of the same formed of fabric material so arranged as to support a plurality of hands of bananas the box further provided with a means for supplying warm air to the bananas to prevent the same from chilling in cold weather and thereby become unsalable.

A still further object of the invention is 50 in the provision of a display rack which is pro-

vided with a fabric cover which may be quickly brought into position to cover the fruit positioned on the display rack and which may be quickly rolled up out of the way to permit the fruit to be exposed to view.

These objects and the several novel features of the invention are hereinafter more fully described and claimed and the preferred form of construction by which these objects are attained is shown in the accompanying 60 drawings in which—

Fig. 1 is a perspective view of my improved display rack.

Fig. 2 is a vertical sectional view taken on line 2—2 of Fig. 1.

Fig. 3 is a vertical transverse sectional view taken on line 3—3 of Fig. 2.

Fig. 4 is a view similar to Fig. 1 showing the means utilized for covering the fruit on display.

Fig. 5 is a detail perspective view of a modified form of fabric support.

Fig. 6 is a top plan view of a display rack embodying the structure as shown in Fig. 5.

It is a well known fact in the fruit, and particularly the banana industry, that when the ends of bananas come in contact with other bananas or when a hand of bananas is laid on a hard unyielding surface that the bananas quickly become spotted and are therefore not readily salable. With my improved structure this difficulty is overcome as the bananas are supported on a looped strip of fabric material which will not bruise the same.

Referring now to the drawings, the display rack comprises the ends walls 1 and 2, the front wall 3, the base 4 and the rear wall 5 which may be provided with a removable back 6. The base 4 has positioned thereon the electric lamps 7 which may be turned on in cold weather to prevent the bananas or fruit on display in the rack from becoming chilled. A thermometer 8 may be also mounted upon the base 4 to register the temperature in the box. It will be noted that the rear end 5 of the box is higher than the front end 3 and that the upper edge of each of the side members 1 and 2 gradually curves 100

downwardly from the rear toward the front of the rack.

The sides 1 and 2 adjacent the curved upper edge thereof are each provided with a plurality of apertures 9 through which the ends of the rod 10 extend. A fabric strip 11 has secured thereto at spaced intervals the relatively narrow strips 12 which form supports for the fabric strip 11 to maintain the same in looped formation on the rods 10 as is more clearly indicated in Fig. 2. Each one of these looped portions 13 is adapted to receive a hand or several hands of bananas and the distance between the rods 10 is of sufficient length to prevent the ends of the bananas of one hand from coming into contact with the bananas of a hand placed in the next higher loop 13. It will be noted that since the loops 13 are arranged in stepped relation that the upper layer of bananas on each hand will be exposed to view.

Referring to Fig. 4, I have shown a means for covering the fruit on display which consist of a fabric strip 15 of sufficient width to permit the edges of the same to lie down over the upper edges of the respective sides 1 and 2. The strip 15 is wound on the roller 16, the same being secured to the display rack by means of the brackets 17 positioned at each end thereof. The roller 16 may be of the curtain roller type so that the strip 15 may be wound thereon or unwound therefrom. The forward edge of the strip is provided with the grips 18 which are adapted to hook over the rod 19 positioned adjacent the forward edge of the display rack. It will thus be seen that the fruit may be completely covered very quickly and easily and in cold weather this is of vital importance in order to maintain fruit in perfect condition.

Referring to Figs. 5 and 6 it will be seen that the fabric strip 20 is engaged at its forward and rear edge by the rods 21 each formed with the downturned ends 22 which are adapted to engage in suitable apertures provided in the upper edge of the side members 23 and 24 of the rack. In this form of construction any one of the fabric strips 20 may be taken out and replaced with a new strip in the event that any one of the same becomes soiled or damaged.

When using the word fabric it is to be understood that it is to be interpreted in its broadest sense and may be composed of any flexible material such as canvas, webbing, paper, netting, rubber or any rubberized material etc.

From the foregoing description it becomes evident that I have provided a novel and useful display rack for fruit, such as bananas, which is provided with a fabric support for the fruit thereby preventing injury to the same due to the weight of the upper layer of bananas on the ones therewith and likewise that the device is so constructed

as to permit the fruit displayed thereon to be maintained at a temperature sufficiently warm to prevent chilling thereof and likewise that the device is extremely cheap to manufacture and assemble and will provide a rack for the attractive display of fruit or the like.

Having thus fully described my invention, its utility and mode of operation, what I claim and desire to secure by Letters Patent of the United States is—

1. A display rack comprising a frame having spaced side members, a series of rod like members in spaced parallel relation, one above the other and to the rear thereof in succession, a fabric material supported by the said rod like members in a series of loops, each loop of the series extending below the first of a pair of rod like members a distance less than the distance between said pair of rods and providing a series of flexible pockets adapted to support fruit or other material practically in full view from the front of the rack.

2. In a display rack for presenting merchandise to the view of purchasers, a frame, a strip of flexible material supported thereby in a series of loops each of said loops having the general form in cross section of an involute curve and the series of loops being so relatively positioned that a line extending from the lower to an upper edge of the loops in succession has the form of an upwardly extending curve within the concave side of which the displayed articles are positioned.

In testimony whereof I sign this specification.

WALTER O. BROWN.
